UNITED STATES PATENT OFFICE.

IRWIN CHASE, OF BAYONNE, NEW JERSEY, ASSIGNOR TO THE ELCO COMPANY, OF BAYONNE, NEW JERSEY, A CORPORATION OF NEW JERSEY.

DESIGN FOR AN ELECTRIC SIDE LIGHT FOR BOATS.

48,364.

Specification for Design.

Patented Jan. 4, 1916.

Application filed April 17, 1915. Serial No. 22,187. Term of patent 14 years.

To all whom it may concern:

Be it known that I, IRWIN CHASE, a citizen of the United States, residing at Bayonne, county of Hudson, and State of New Jersey, have invented a new, original, and ornamental Design for Electric Side Lights for Boats, of which the following is a specification, reference being had to the accompanying drawings, forming a part thereof.

Figure 1 is a side elevation of the side light showing my new design, and Fig. 2 is a plan view of the same.

I claim:

The ornamental design for an electric side light for boats as shown.

In testimony whereof I hereby affix my signature.

IRWIN CHASE.
